UNITED STATES PATENT OFFICE.

ANDREW F. SHULER, OF ARCANUM, OHIO; MARY M. SHULER AND W. B. SHULER, EXECUTORS OF SAID ANDREW F. SHULER, DECEASED, ASSIGNEES TO H. M. SHEER COMPANY, OF QUINCY, ILLINOIS.

BROODER.

REISSUED

Application filed October 9, 1922. Serial No. 593,343.

This invention relates to brooders for chicks and the like.

One object of the invention is to provide a brooder of a simple, durable construction, 5 the hood of which will be of such a character that access may be had to all parts thereof through a suitable opening.

Other objects of the invention will appear as the device is described in detail.

10 In the accompanying drawings Fig. 1 is a plan view of a brooder embodying my invention, partly broken away; Fig. 2 is a side elevation of the same with one shutter open; and Fig. 3 is a section taken on the 15 line 3—3 of Fig. 1.

In these drawings I have illustrated one embodiment of my invention and have shown the same as comprising a heater, or stove, consisting of a base 1, a fire bowl 2 mounted on a base and having its upper portion of greater diameter than its lower portion, and a cylindrical portion 3 mounted on the upper end of the fire bowl and having in its top an opening through which fuel 20 may be fed to the fire, this opening being closed by the usual stove lid 4. An outlet pipe 5 for the products of combustion is connected with the cylindrical portion 3 near the top thereof and is here shown in the 25 form of an elbow, the outer end of which may be connected with a stove pipe of suitable length. A baffle 6 extends across the inner end of the outlet pipe and is open at its ends and bottom, but closed at the top, 30 so that to permit the passage of smoke and gases, but to prevent solid matter from entering the pipe.

A hover extends about and is supported by the stove, or heater, and, as here shown, 35 comprises a hood 7 having a central opening to permit it to be placed about the heater and having in one side thereof an opening through which access may be had to the base of the heater to regulate the 40 fire, remove ashes, etc., and which also permits the space beneath the hover to be cleaned. In order that all space beneath the 45 hover may be accessible through the opening the hover as a whole is rotatably mounted on the heater so that the opening may be moved to any side of the heater. The 50 hover may be of any desired construction and may be mounted upon a heater in any desired manner, but in the present instance the upper cylindrical portion 3 of the heater 55 has an outwardly extending ledge, or flange, 8 and the hover comprises a ring of metal 9 which extends about the heater and rests upon this flange. The main portion, or hood 60 of the hover, which is shown at 7, is secured to this ring by means of bolts, or rivets, 10. The central portion of the hood is preferably continuous and forms an unbroken circle about the heater and the outer portion of the hood is cut away on one side 65 thereof, as shown at 11, to provide the opening through which access is had to the space beneath the hover. This opening is of less width than the width of the hood and, therefore, the central portion of the hood is not 70 broken, but is continuous. The hover may be reinforced at its outer edge in any suitable manner, as by a wire extending entirely about the same and secured thereto in the manner which is customary in reinforcing 75 sheet metal. The opening 11 may be closed by a movable closure of any suitable kind but as here shown I have employed two shutters 12 which are hinged at their opposite edges to the hood at the respective 80 edges of the opening. Preferably the shutters overlap both the central portion of the hood and the edge portions thereof adjacent to the opening, the hinges 13 being spaced short distances from the edges of the 85 opening. I also prefer that the shutters should overlap one another at their meeting edges and I have shown one shutter as provided with a clip 14 to extend over the other and retain them in their proper overlapping positions. The edges of the hood 90 adjacent to the opening may be reinforced in any desired manner and in the present construction I have employed brace rods 15, the outer ends of which are bent to form 95 hooks 16 which extend through the edge portions of the hood, and the inner ends of which are connected at points above the hood with brackets 17 rigidly secured to the hood and the ring 9. The connections between 100 the rods and the brackets are preferably formed by nuts 18 which permit of the rods being adjusted to support the edges of the hood in the proper positions. It will be apparent, therefore, that the hover as a whole 105 comprises a continuous circular portion which is rotatably mounted upon the heater so that the opening in the hood may be

5 moved into any desired position with relation to the heater. Further, it will be apparent, that the hover as a whole may be lifted from the stove by removing the elbow 5 and the controlling arm, which will be hereinafter described, by tilting the same to enable one side of the ring to clear that edge of the heater opposite the elbow.

10 The outlet pipe, or elbow, 5 is provided on the outside of the heater and between its ends with an opening 19 which may be closed by a damper 20. This damper is adjusted to control the draft through the pipe by means of a thermostat 21 which is carried 15 by an arm 22 rigidly secured to the heater and is connected with one end of a lever 23 pivotally mounted on brackets 24 carried by the arm 22 and having its other end connected with the damper 20. The arrangement is such that the expansion and 20 contraction of the thermostat will cause the damper to be raised or lowered, thus regulating the draft and the fire. The amount of movement imparted to the damper by the 25 thermostat may be controlled by a thumb nut, or other suitable device 25 and it will be noted that the arrangement of thermostatic control is entirely above the hover and is so arranged that it is readily accessible for adjustment or other purpose, and, further, that its operation will not be interfered with by the chicks roosting on the 30 same, as is frequently the case when it is beneath the hover. Ordinarily the difference 35 between the temperature beneath the hover and that above the same will not interfere with the correct regulation of the temperature beneath the hover, because the thermostat may be adjusted to maintain the desired 40 temperature beneath the hover. In the event difficulty should be experienced, under certain conditions, due to this difference in temperature, it can be readily overcome by permitting the warm air from beneath the 45 hover to escape through an opening in the hover arranged directly beneath the thermostat so that the warm air will come in contact with the thermostat. The opening may be controlled in any suitable manner. With

the present construction this result would be 50 accomplished by rotating the hover to bring the shutters directly beneath the thermostat and then securing the shutters in a partially open position so that the warm air could escape upwardly therefrom in contact with 55 the thermostat.

It will be apparent that the brooder as a whole is of a very simple, durable construction, the stove having a large capacity and the hover being of such a construction and 60 arrangement that it may be strongly built and access had to the space beneath the same on all sides of the heater through a suitable opening. Further, the controlling device, as has been stated, is readily accessible. 65

While I have shown and described one embodiment of my invention I wish it to be understood that I do not desire to be limited to the details thereof as various modifications may occur to a person skilled in the 70 art.

Having now fully described my invention what I claim as new and desire to secure by Letters Patent is:

1. In a brooder, a heater, a hover having 75 a continuous relatively narrow inner portion supported by said heater and having its outer portion cut away on one side thereof to form an opening extending from said inner portion through the outer edge of said 80 hover, a movable closure for said opening, and rods connected with said inner portion and with the outer edge of said hover at the respective sides of said opening to support the outer edge of said hover at the lateral 85 edges of said opening.

2. In a brooder, a heater, a hover comprising a ring extending about and rotatably supported on said heater, a hood supported by and extending outwardly from said ring and having an opening in one side thereof, and a closure hinged to the lateral edge of said opening and supported by said ring when in its closed position. 90

In testimony whereof, I affix my signature hereto. 95

ANDREW F. SHULER.
